United States Patent Office

Des. 203,056
Patented Nov. 30, 1965

203,056

SPATULA

Harold O. Henning, Park Ridge, Ill., assignor to Club Aluminum Products Company, La Grange Park, Ill., a corporation of Illinois

Filed Oct. 29, 1964, Ser. No. 82,386

Term of patent 14 years

(Cl. D44—29)

FIG. 1 is a perspective view of a spatula showing my new design;

FIG. 2 is an enlarged scale top plan view of the blade portion;

FIG. 3 is an elevational view taken from the bottom of FIG. 2;

FIG. 4 is an elevational view taken from the left of FIG. 2;

FIG. 5 is an elevational view taken from the right of FIG. 2; and

FIG. 6 is a fragmentary bottom plan view.

The essential features of my new design are shown in full lines and reside primarily in the particular configuration and converging arrangement of the club-like apertures with respect to the converging side walls, in combination with the downwardly-slanted frontal portion of the blade.

I claim:

The ornamental design for a spatula, as shown and described.
